CLAIM

The ornamental design for a shoe sole, as shown and
described.

DESCRIPTION

FIG. 1 is a bottom plan view of a shoe sole showing my
new design, the top being plain and unornamented;
 FIG. 2 is a left side elevational view thereof;
 FIG. 3 is a right side elevational view thereof;
 FIG. 4 is a front elevational view thereof; and
 FIG. 5 is a rear elevational view thereof.

The broken line showing of a shoe in FIGS. 1-5 and the
area within are environmental only and form no part of
the claimed design.
